UNITED STATES PATENT OFFICE.

MELVILLE D. JONES, OF BOSTON, MASSACHUSETTS.

DESIGN FOR IRON PEDESTALS.

Specification forming part of Letters Patent No. 5,539, dated February 13, 1872.

Specification describing a Design for an Iron Pedestal, invented by MELVILLE D. JONES, of Boston, in the county of Suffolk and State of Massachusetts.

The nature of my design is fully represented in the accompanying drawing to which reference is made.

The drawing represents the front and only ornamental part of the pedestal. A raised edge runs around the face of the pedestal, and

in the center are raised figures, the whole face being flat.

What I claim as my invention is—

A design for a pedestal, ornamented substantially in the manner above described, and the general outline of the pedestal, as shown in the drawing.
